UNITED STATES PATENT OFFICE.

MARSHALL W. PIPER, OF WOLFBORO, NEW HAMPSHIRE.

COIN-RECEIVER.

No. 920,177.

Specification of Letters Patent.

Patented May 4, 1909.

Application filed May 9, 1908. Serial No. 431,988.

To all whom it may concern:

Be it known that I, MARSHALL W. PIPER, a citizen of the United States, residing at Wolfboro, in the county of Carroll, State of New Hampshire, have invented certain new and useful Improvements in Coin-Receipters; and I do hereby declare the following to be a full, clear, and exact description of the invention, such as will enable others skilled in the art to which it appertains to make and use the same.

This invention relates to coin handling devices and is designed for conveniently transferring coin from a merchant to his customer in making change, or from a customer to the merchant when paying for goods, and has for one of its objects to simplify and improve the construction of devices of this character.

Another object of the invention is to provide a simply constructed device of this character which will remain poised against accidental displacement but which will yield readily when required to be used.

Another object of the invention is to provide a simply constructed device of this character operative from either side and which will remain poised against accidental displacement, but which will yield when applied to either side when required for use.

With these and other objects in view the invention consists in certain novel features of construction as hereafter shown and described and then specifically pointed out in the claim, and in the drawings illustrating the preferred embodiment of the invention, Figure 1 is a side elevation of the improved device, Fig. 2 is an end elevation, and Fig. 3 is a plan view.

The improved device comprises a base 10 of any suitable shape, but which will generally be oblong and preferably in ornamental outline and provided with two spaced standards 11-12 extending vertically for a distance and then curving inwardly at 13-14 and then extending vertically again at 15-16, the vertical terminals 15-16 provided with horizontally alined apertures 17, the apertures having flat lower sides 19, the ends of the flat portions merging at reverse angles into the sides of the aperture as shown at 20-21.

The receptacle for the coin is represented at 22, and preferably in shallow dish shape and with trunnions or pivot pins 23-24 extending from its sides and through the apertures 17, the lower faces of the pins being

flat to correspond to the flat faces of the apertures, so that the receptacle is supported in horizontal position against accidental displacement, as hereafter explained.

Depending from the receptacle 22 is a push plate 25, preferably with its contour corresponding to the inner faces of the standards 11-12 and the curved portions 13-14 thereof, as shown.

With the device thus constructed it will be obvious that the receptacle 22 will be retained in horizontal position, and will require some pressure to overcome the inertia of the superimposed flat surfaces 19 of the apertures 17 and the pins 23-24, so that when coins are placed in the receptacle the latter will not be overturned, or caused to vibrate, while at the same time a relatively slight pressure against the push plate 25 will overturn the receptacle and discharge the coin.

The device will be deposited generally upon the counter in retail stores, or other localities where it is customary to pass coins back and forth from a counter in making change or in paying for goods and when a customer pays for goods he deposits the coin in the receptacle and the clerk or merchant on the opposite side of the counter presents the open hand with the palm upward to the device and pushes with the ends of the fingers against the push plate 25 which will overturn the receptacle 22 and discharge the coins into his hand, and the merchant in giving change deposits the change in the receptacle and the customer repeats the operation above described from the opposite side of the device and thus discharges the coin into his hand in the same manner. Thus both the customer and the merchant are relieved from the trouble and difficulty often experienced in transferring coins from one person to another.

The device is simple in construction, can be inexpensively manufactured, and operates effectually for the purposes described.

The device may be constructed in any required size and of any required material, but will generally be constructed of metal and suitably plated or otherwise ornamented, and will constitute an ornamental addition to the fixtures of a store or other localities where it is employed.

What is claimed, is:—

A device of the class described comprising a base, spaced vertical standards rising from said base and provided with transverse bear-

ing apertures having horizontal lower faces and with the side walls thereof arranged at angles extending in opposite directions from the horizontal portion, a coin receiver having 5 a depending plate and oppositely extending pivot members formed with flat lower faces and round upper sides and bearing by the flat faces upon the horizontal faces of the apertures with the junctures of the flat faces

and rounded sides of the pivot located at the 10 junctures of the horizontal bottom faces and the inclined side walls of the apertures.

In testimony whereof, I affix my signature, in presence of two witnesses.

MARSHALL W. PIPER.
